UNITED STATES PATENT OFFICE.

JAMES DIXON ASQUITH, OF LEEDS, ENGLAND.

MACHINE FOR MILLING FABRICS.

SPECIFICATION forming part of Letters Patent No. 746,912, dated December 15, 1903.

Application filed August 13, 1902. Serial No. 119,493. (No model.)

To all whom it may concern:

Be it known that I, JAMES DIXON ASQUITH, a subject of the King of Great Britain, residing at Leeds, county of York, England, have 5 invented certain new and useful Improvements in Machines for Milling Fabrics, of which the following is a full and complete specification, such as will enable those skilled in the art to which it appertains to make and 10 use the same.

The object of this invention is to provide an improved mechanism for the "milling" of textile fabrics in a more efficient and expeditious manner than is the case at the present 15 time and also to remove "rugs" and "creases" formed in the fabrics when being "milled" by the milling-rollers.

The milling-machine to which I apply my invention is similar to those in general use, 20 with the exception that the top, bottom, and sides of the spout at the end from which the fabric issues in the milling process are made shorter than usual; but the bottom of the 25 spout has an addition of an inclined plate, of wood or other material, at its outlet end for the purpose of keeping the fabric in position for the improved mechanism to act upon it.

This invention is fully disclosed in the following specification, of which the accompanying 30 drawings form a part, in which the separate parts of my improvement are designated by the same reference characters in each of the views, and in which—

Figure 1 is a side elevation of my improved 35 fabric-milling machine; Fig. 2, a sectional plan thereof; Fig. 3, a view similar to Fig. 2, but showing the parts in a different position; and Fig. 4, a side elevation showing the fabric in position for being acted upon by the 40 improved mechanism.

In carrying out my invention shaft-bearings *f* are fixed one on each side of the frame *a* of the machine, and in these bearings *f* a shaft *g* is put. This shaft *g* runs underneath 45 the end of the spout *e* and parallel with the driving-shaft *b*, upon which is the bottom milling-roller *c*. Upon one end of the driving-shaft *b* a chain-wheel *h* is keyed, and a chain-wheel *i* is also keyed on the end of the 50 shaft *g* on the same side of the machine. These chain-wheels *h* and *i* are geared together by an endless chain *j*. Upon the sides

of the frame *a* bearings *k* are fixed, each bearing *k* being on a level with and in front of the spout *e*. In these bearings *k* shafts *l* are 55 placed, these shafts *l* being parallel with the driving-shaft *b* and the shaft *g*. On the outer end of each shaft *l* a barrel-casting *m* is fixed, and upon the reverse ends of the shafts *l* blocks of wood *n* are bolted. 60

At the bottom of the outlet end of the spout *e* an inclined plate *x* is fixed under the blocks *n* and the blocks *n* rest upon it.

In bearings *o* on each side of the frame *a* vertical shafts *p* are put, and upon the upper 65 parts of the shafts *p* levers *q* are keyed, the reverse end of each lever *q* having upon it a fork *r*, these forks *r* fitting into the barrel-castings *m*.

Upon the lower part *s* of the shaft *p* a second lever *s* is keyed, the reverse ends of these levers *s* being put upon bolt-headed studs *t*, upon which they work loosely. Upon each end of the shaft *g* a face-plate *u* is keyed. These face-plates *u* each carry a fixed stud 75 *v*, upon which one end of a connecting-rod *w* works loosely, the reverse ends of the rods *w* being put upon and working loosely upon the bolt-headed studs *t*.

The working of the invention is as follows: 80 One end of the fabric *z* is passed through a hole in the draft-board *y*, then over a guide-roller, then between the milling-rollers *c* and *d*, then through the spout *e*, and over the plate *x* and between the blocks *n* and down 85 into the bottom of the machine. The two ends of the fabric *z* are then stitched together, making an endless band of the fabric *z*. Thus the fabric can be run continuously through the machine until the milling operation is completed. Before the machine is set in motion the position of the improved mechanism is as shown in Fig. 2. The machine being set in motion from the driving-shaft *b*, motion is transmitted to the chain-wheels *h* and *i*, the shaft *g*, the face-plates *u*, the connecting-rods *w*, the levers *s* and *q* on the vertical shafts *p*, so that the forks *r* of the levers *q*, working in the barrel-castings *m*, cause the shafts *l*, on which are the blocks *n*, to move 95 toward each other to the position shown in Fig. 3 and then to recede to the original position, as in Fig. 2, these forward and receding movements continuing as long as the machine 100

chine is in motion. The rollers *c* and *d* as the fabric *z* is running between them "mill" the fabric *z* to a required length and width; but in this process of milling rigs or creases 5 are often formed in the fabric *z* by the action of the rollers *c* and *d*; but upon the passage of the fabric *z* over the plate *x* of the spout *e* and between the blocks *c*, which slide upon the plate *x*, the blocks *c* in their forward 10 movement toward each other give an additional milling to the fabric *z* by pressing and squeezing it, and at the same time press and squeeze out rigs or creases that may have formed in the fabric *z* and the blocks *n*. 15 These recede to their original position.

Having fully described my invention, what I claim as new, and desire to secure by Letters Patent, is—

1. A machine for milling fabrics provided 20 with the usual milling-rollers and a spout, and laterally-movable shafts arranged at the delivery end of said spout and provided at their inner ends with blocks, and means for operating said shafts, substantially as shown 25 and described.

2. A machine for milling fabrics provided with the usual milling-rollers and a spout, and laterally-movable shafts arranged at the delivery end of the said spout and provided 30 at their inner ends with blocks, and means for operating said shafts, consisting of vertically-arranged shafts provided with arms in 35 operative connection with said laterally-movable shafts, and devices for operating said vertically-arranged shafts, substantially as shown and described.

3. A combination with a machine for milling fabrics provided with the usual milling-rollers and a spout, of laterally-movable 40 shafts mounted at the delivery end of said

spout and provided at their inner or adjacent ends with blocks, vertically arranged and operating shafts provided at their upper ends with forked levers in operative connection with the outer ends of said laterally-movable 45 shafts, a supplemental shaft mounted transversely of the machine below said spout and means whereby said supplemental shaft is adapted to operate said vertically-arranged shafts, substantially as shown and described. 50

4. The combination with a machine for milling fabrics provided with the usual milling-rollers and a spout, of laterally-movable shafts mounted at the delivery end of said spout and provided at their inner or adjacent 55 ends with blocks, vertically arranged and operating shafts provided at their upper ends with forked levers in operative connection with the outer ends of said laterally-movable shafts, a supplemental shaft mounted transversely of the machine below said spout, and means whereby said supplemental shaft is 60 adapted to operate said vertically-arranged shafts, consisting of face-plates connected with the ends of the supplemental shafts and 65 provided with crank-pins, arms connected with the lower ends of the vertically-arranged shafts, and crank-levers connected with said arms and adapted to be operated by said crank-pins, substantially as shown and de- 70 scribed.

In testimony that I claim the foregoing as my invention I have signed my name, in presence of the subscribing witnesses, this 29th day of July, 1902.

JAMES DIXON ASQUITH.

Witnesses:

TOM LAMBERT WILSON,
HORATIO LORD.
